UNITED STATES PATENT OFFICE.

DANTE SILVESTRI, OF ROME, ITALY.

RESILIENT-HUB WHEEL.

1,140,622.

Specification of Letters Patent. Patented May 25, 1915.

Application filed December 6, 1911. Serial No. 664,146.

To all whom it may concern:

Be it known that I, DANTE SILVESTRI, a subject of the King of Italy, residing at Rome, in the Kingdom of Italy, have invented new and useful Improvements in Resilient-Hub Wheels, of which the following is a specification.

The present invention relates to a resilient hub for wheels of road vehicles which is also applicable to vehicles running on rails.

The invention has more particularly for its object a hub, the operating members of which have the form of two disks of very hard steel, the surfaces of which are formed with prismatic projections and radial and co-axial recesses or inclined contact surfaces in such a manner that by reason of the reciprocal contact surfaces, a stable support is insured in every direction (that is in the normal and vertical planes of the concentric external structure forming the cover of the housing) thus providing a complete resilient action for the hub. This resilient action consists in transforming and absorbing the shocks due to the uneven surface of the road, as well as in eliminating torsional stress of the axle in order to give the least possible disturbance to the vehicle, but without producing lateral displacements to the complicated parts of the wheel. This object is attained by applying to the axle, a movable concentric disk which, under spring action or similar resilient means, is pressed against another disk rigidly fitted to a convenient part of the metal hub containing and guiding the members which control the resilient action of the apparatus.

The first disk referred to is free to move in endwise direction to the axle and by overcoming the elastic resistance which acts upon the disk, it determines the reciprocal normal displacement of the second disk whereby a combined turning and sliding movement of the mechanism is effected.

As both disks are formed with recesses and corresponding prismatic projections any angular displacement of the rigidly mounted disk relatively to the movable disk will produce a sliding movement of said movable disk in the endwise direction of the axle and, by overcoming the resistance of the springs or other resilient means acting upon the said disk, road shocks and lateral thrusts become absorbed.

The invention is shown in the accompanying drawings, in which:

Figure I is a transverse section of the mechanism arranged in the interior of the hollow hub shown in the normal position; Figs. II and III are corresponding views of the mechanism in use displaced downwardly and upwardly respectively; Figs. IV and V are front views of the movable disk 4 and disk 5 fixed to the casing 1', the surfaces of the two disks having recesses and radial prismatic projections and co-axial sector-shaped portions; Figs. VI and VII are transverse sections of the two disks symmetrically disposed corresponding to the position shown in Figs. I, II, and III.

The metallic structure 1, 1', 2, 3, 13 which forms the casing or housing in which the apparatus is placed and guided, consists of a box or chamber of cylindrical form and limited by the walls 1, 1', in which can turn radially over a distance corresponding to the maximum displacement permissible, a second box or chamber 2 which is mounted upon the sleeve 3 upon which is seated a disk 4 guided by the flanges 11 and 12.

The disk 4 is held in elastic contact with a disk 5 by spiral springs 6 inclosed in the chamber 2.

The disk 5 is secured to the part 1' of the external casing and is in contact with the disk 4 by its inclined surfaces 14, 15, 16, 17 in the form of isosceles triangular prisms the meeting edges or ridges of which are extended in radial direction to the circumference of the disk as shown in Fig. IV, while Fig. V shows the parts or prisms which project or are raised, on the disk 4 and which correspond with recessed portions of the disk 5 and vice versa. These corresponding parts or faces on the disk 5 have the same reference numerals as the parts in disk 4 but with indices, viz: 14', 15', 16', 17'. Between successive prisms are conical sector-shaped portions 20, 21 which are concentric to the axis and oppositely inclined to each other.

In Figs. IV and V are shown disks with 4 prisms and corresponding recesses, adapted to provide elastic action of the mechanism, but any other number of prisms may be used. The Figs. I, II, and III clearly show the action of both disks when they are in contact with each other. For instance, if

by reason of a shock, the wheel is caused to rise, see Fig. II, the disk 5 also rises and by pressing against the conical concentric upper faces 21, 20 and against the lower faces 14—16 of the radial prisms of the disk 4, has 6 points of contact so causing the disk 4 to move longitudinally to the axis, thereby compressing the springs 6, which take up the shock in a horizontal direction. The successive conical faces 20, 21 and the upper faces 17—15 and 15—17 of the radial prisms become separated by this movement so that friction is lessened; the same effect is obtained with the opposite movement of the wheel, that is to say when the wheel enters a rut, see Fig. III. In a similar manner there will always be the same 6 points of contact of the opposite lower conical faces 21—21' and 20—20' and of the faces 15 and 15' of the radial prisms with corresponding separation of other surfaces when the shock is received in a direction intermediate of the ridges 18 and 19. Rotary movement is transmitted to the wheel to which the mechanism is secured, through the intervention of the inclined faces of the radial prisms; therefore with this transmission or elastic drive there is always the sliding movement, in longitudinal direction, of the disk 5 which slides upon the sleeve 3 and in the chamber 2 while rotating with them owing to longitudinal guideways and keys on the top flange 12 of the disk 4.

To prevent dust from entering, cover plates 7 are fitted outside the walls 1, 1' and one of said cover plates may be formed by the plate 13 which serves as an intervening member for transmitting the power. By means of leather rings placed in circular grooves 8—8 in said plates 7 and 13, hermetic joints are provided. In the drawings, the axle is represented as mounted in ball bearings 9—10. When the shock or tor-

sional strain has ceased, the parts are caused to return to their normal position by 45 the springs 6 so that the hub is self-centering and the radial prismatic projections and concentric sector-shaped portions will constantly tend to return the two co-acting disks to the concentric position in an elastic manner so that the axle can turn the wheel, connected with the hub-mechanism, without receiving shocks through a rigid assemblage. 55

I claim:

1. A self-centering resilient hub for vehicles comprising an outer and an inner hub-box, a wheel-body firmly connected with the outer box, the central sleeve connected with the inner box, two friction disks with in the latter having a plurality of inclined contact surfaces of radial prismatic form in the faces of said disks, a sliding connection between one of said disks and the inner hub-box, and elastic means for pressing the said disks together, as and for the purpose stated. 60

2. In a resilient wheel, the combination with a wheel-body and an outer divided hollow metallic hub-box, of an inner hub-box, an integral concentric hollow boss on the latter, a sleeve fast in the inner hub-box, a rear plate integral with said sleeve, an alternately recessed and embossed flanged friction disk seated upon said sleeve and slidably held in the inner hub-box, a spiral 75 spring between the side wall of the latter and the adjacent face of said friction disk, a corresponding rear friction disk at the opposite face of said friction disk, a large central opening in the rear friction disk, and a 80 rigid connection between the latter and the said outer hub-box. 75

DANTE SILVESTRI.
